Primary Examiner — T. Chase Nelson*Assistant Examiner* — Eric L Goodman(74) *Attorney, Agent, or Firm* — Fish & Richardson P.C.(57) **CLAIM**

The ornamental design for a medical device adaptor, as shown and described.

DESCRIPTION

FIG. 1 is a perspective view of a medical device adaptor. FIG. 2 is a side view of the medical device adaptor of FIG. 1. FIG. 3 is a side view of the medical device adaptor of FIG. 1. FIG. 4 is a side view of the medical device adaptor of FIG. 1. FIG. 5 is a side view of the medical device adaptor of FIG. 1. FIG. 6 is a top view of the medical device adaptor of FIG. 1. FIG. 7 is a bottom view of the medical device adaptor of FIG. 1; and, FIG. 8 is another perspective view of the medical device adaptor of FIG. 1.
